DESIGN FOR A FISH LURE

Zigmunt M. Wasielewski, Kenmore, N. Y.

Application October 20, 1948, Serial No. 149,203

Term of patent 7 years

(Cl. D31—4)

To all whom it may concern:

Be it known that I, Zigmunt M. Wasielewski, a citizen of United States of America, residing in Kenmore, in the county of Erie and State of New York, have invented a new, original, and ornamental Design for a Fish Lure, of which the following is a specification, reference being made to the accompanying drawing, forming a part thereof.

I claim:

The ornamental design for a fish lure, substantially as shown.

ZIGMUNT M. WASIELEWSKI.
